(57) **CLAIM**

I claim, the ornamental design for a jewelry chain, as shown and described.

DESCRIPTION

FIG. 1 is a front side elevation view of a jewelry chain, showing my new design, the opposite rear side and the orthogonal top and bottom sides being mirror images thereof;

FIG. 2 is a perspective view thereof with the jewelry chain in an alternate position; and,

FIG. 3 is an enlarged partial perspective view thereof showing two links of the jewelry chain.

1 Claim, 3 Drawing Sheets
